UNITED STATES PATENT OFFICE.

JOHN I. ASNER, OF BALTIMORE, MARYLAND.

FINGER-GUARD FOR SEWING-MACHINES.

1,370,262.

Specification of Letters Patent.

Patented Mar. 1, 1921.

Application filed July 22, 1920. Serial No. 398,051.

To all whom it may concern:

Be it known that I, JOHN I. ASNER, a citizen of the United States of America, residing at Baltimore, State of Maryland, 5 have invented certain new and useful Improvements in Finger-Guards for Sewing-Machines, of which the following is a specification.

This invention relates to sewing machines 10 and has special reference to a finger guard for the presser foot of a sewing machine.

One important object of the invention is to provide an improved and simplified finger guard which can be applied to the 15 presser foot of practically any sewing machine and will act to prevent the operator's finger from getting beneath the needle.

A second important object of the invention is to provide a device of this description which can be made from a blank of 20 sheet metal.

With the above and other objects in view, the invention consists in general of certain 25 novel details of construction and arrangements of parts hereinafter fully described, illustrated in the accompanying drawings, and specifically claimed.

In the accompanying drawings, like characters of reference indicate like parts in the 30 several views, and:—

Figure 1 is a perspective view of a portion of a sewing machine showing one form of my invention applied thereto.

Fig. 2 is a side elevation of the presser 35 foot and associated parts showing the guard in section applied to the presser foot.

Fig. 3 is a plan view of the part shown in Fig. 2.

Fig. 4 is a perspective view of the guard 40 removed.

Fig. 5 is a detail showing the blank from which the guard is formed.

Fig. 6 is a view similar to Fig. 1 but showing a modified form of guard.

Fig. 7 is a view similar to Fig. 3 of the modified form.

Fig. 8 is a perspective view of the modified form removed from the presser foot.

Fig. 9 is a view of the blank from which 50 the modified form is made.

In the drawings illustrating the invention there is shown a presser bar 10, presser foot 11, needle bar 12 and needle 13 all

of ordinary and well known form such as are used on many sewing machines. 55

The presser foot is provided with the usual upturned end 14 and, as is common in machines, this upturned end is somewhat longer than the other side of the presser foot and the needle passes between the two 60 sides as shown.

The guard itself is formed from a single blank of sheet metal by preference. Each blank consists of a main rectangular body portion 15 divided by transverse fold line 16

so that this portion of the body may be folded at these lines to form a cuff as indicated at 17, the under part of which is beveled at 17', which can be slipped over the upturned end 14 of the presser foot. The 70 upper side of this cuff is provided with a screw thread opening 18 wherein fits a screw 19 serving to lock the cuff in position on the presser foot. In the form shown in Fig. 9 there projects from the body 15 a lateral 75 portion 20 extended at one end as at 21, the latter portion being defined from the body by a fold line 22, and, in the completed article, being bent up on this fold line 22 to constitute a guard or barrier 23. This construction is also followed in the form shown in Fig. 5 but, in addition, an extension is formed on the portion 20 which is divided therefrom by a fold line 24, the extension being curved as shown at 25 in Fig. 5, and when bent on the fold line in the completed article forming a side guard 26 to protect the finger from slipping laterally beneath the needle. 80

In use the cuff 17 is simply slipped over 90 the end of the presser foot and the screw 19 screwed down. The device will then be in position so that in each form the finger of the operator will be prevented from slipping beneath the needle from the front of 95 the presser foot by the guard 23 and, in the form shown in Figs. 1 to 5, the finger will be prevented from slipping laterally by the guard 26.

There has thus been provided a simple 100 and efficient device of the kind described and for the purpose specified.

Having thus described the invention, what is claimed as new, is:

1. A finger guard for sewing machine 105 presser feet comprising a cuff adapted to fit

over the toe of a presser foot, a guard plate formed on said cuff and having a portion projecting upwardly in front of the presser foot and a second portion projecting upwardly at the side of the presser foot, and means to releasably hold the guard on the presser foot.

2. A finger guard for sewing machine presser feet constructed of a single piece

of sheet metal having a body portion adapted to be folded to form a cuff, and a portion projecting laterally therefrom adapted to be folded to be bent upward to form a guard, in combination with means to releasably hold the cuff on a presser foot.

15

In testimony whereof I affix my signature.

JOHN I. ASNER.
